UNITED STATES PATENT OFFICE.

HARVEY C. ALDRICH, OF NORWICH, CONNECTICUT, ASSIGNOR, BY DIRECT AND MESNE ASSIGNMENTS, OF ELEVEN-TWELFTHS TO WM. H. BABCOCK, OF SAME PLACE, GEORGE H. ALDRICH AND RICHARD V. D. WOOD, BOTH OF ORANGETOWN, AND HENRY C. TOWNSEND, OF NEW YORK, N. Y.

LOCK.

SPECIFICATION forming part of Letters Patent No. 256,263, dated April 11, 1882.

Application filed February 2, 1881. (Model.)

To all whom it may concern:

Be it known that I, HARVEY C. ALDRICH, a citizen of the United States, residing at Norwich, in the county of New London and State 5 of Connecticut, have invented certain new and useful Improvements in Locks, of which the following is a specification.

The general object of my invention is to improve the simplicity and cheapness of locks, 10 and at the same time to make it possible to construct a lock with very few pieces that shall be as secure from picking and tampering with as more complicated locks employing a multiplicity of tumblers and internal parts.

15 My invention relates more particularly to the construction of a tumbler and the manner in which it is made to operate in conjunction with the other parts of the lock. Instead of employing a number of separate tumblers, as 20 has heretofore been found necessary in order to give a reasonable degree of security to the lock, I make use of what may be termed a "single" tumbler, provided with one or more locking or dogging points, so disposed that 25 the key, when inserted in the lock to act upon the tumbler or part with which it is connected and with which it moves, propels the same or 30 imparts a positive movement thereto in a direction to cause the one or more lugs, pins, or 35 projections upon the tumbler to pass one or more notches, slots, perforations, or recesses in the key itself. The tumbler may lock, detain, or control the movements of the lock 40 mechanism in any desirable manner, so that, unless the key be properly notched, slotted, 45 perforated, or recessed to correspond with the one or more dogs, lugs, or projections upon the tumbler, the said dogs, lugs, or projections upon the tumbler will be forced into contact 50 with the key by the movement of the latter, and be thus prevented from completing the movement necessary to unlock the parts.

Having now described the general principles 45 of my invention, I will proceed to describe some of the ways in which it may be carried 55 into practice, and in which a tumbler constructed in accordance with that principle may be applied to locks.

In the accompanying drawings, Figure 1 is a perspective view, showing one method of applying my invention to padlocks. Fig. 2 is a side view of a notched key adapted to allow lugs arranged as shown upon the tumbler to pass through the key. Fig. 3 shows my invention applied to a night-latch of simple construction. Fig. 4 is a face view of a tumbler, showing a single lug or projection differently disposed from those shown in Fig. 1, and a perforated key adapted for use with a tumbler of the form shown in this figure.

Referring to Fig. 1, A shows the hasp or shackle of the padlock, provided with a catch, x, upon its end, adapted to engage with and be locked by a hook or latch, c, upon the end of or carried by the tumbler M, the latter consisting in the present case of a pivoted piece pivoted upon a stud in the casing and provided with lugs or projections d d d, disposed at different distances from its end. As here shown, the lugs or projections extend from the edge 65 of the tumbler partially across its face, the two extreme projections starting from the upper and the intermediate one from the lower edge.

The key B is correspondingly notched, as 70 shown in Fig. 2. A spring for causing the hook or catch upon the tumbler to engage with the hasp is indicated at f. The key is inserted through a slot at the bottom of the case, and is guided so that its end will impinge against 75 a projection, h, upon the pivoted tumbler and swing or propel the same against the action of the spring so as to unlock the hasp. At the same time the lugs are propelled toward the side of the key and enter or pass the openings 80 upon the key.

Should an improperly-constructed key be inserted, one or more of the lugs or projections will come into contact with the key and stop the movement of the tumbler and the key before the hasp is unlocked.

As will be observed, the lugs or projections extend across the face beyond the medial line, so as to overlap one another and prevent the insertion of a small wire.

It is obvious that the lugs may be disposed

in very many ways, both with regard to the length and to the width of the tumbler, and that they may be variously shaped.

Many modifications in this respect will readily suggest themselves, and as many lugs or projections may be used as is deemed desirable.

The application of the device to a night-latch will be readily understood from Fig. 3. The key is here represented as inserted and the bolt or latch H withdrawn. As here shown, the tumbler is connected with the latch by means of a pin, P, upon the latch and a slot in the tumbler M. The key moves the latch and tumbler simultaneously.

I do not desire to limit myself to any particular form or disposition of the lugs or projections, or to any particular form of or method of mounting the part to which they are attached, as it is obviously within the scope of the invention to vary these particulars in many ways, so long as the parts are so arranged that the key, properly slotted, recessed, or perforated, propels or moves the lugs or projections upon the tumbler so as to cause them to pass or avoid the key; nor do I limit myself to any particular form of the immediate locking or unlocking devices which detain the bolt or mechanism and are controlled by the tumbler, as there are very many ways of employing such devices in conjunction with a tumbler, and my invention lies wholly in the tumbler

and key combined as herein set forth. I have shown two ways of using a tumbler and key constructed in accordance with this principle; 35 but many others may be employed without departing from the spirit of the invention. By the use of a single tumbler provided with a multiplicity of lugs or projections I attain all the security that is at present attained by the employment of a number of separate tumblers. 40

What I claim is—

1. The combination, substantially as described, of a tumbler provided with one or more lugs or projections and a key suitably slotted, recessed, perforated, or notched, and adapted to act upon or propel the tumbler in substantially the manner described, whereby the lugs or projections upon the latter, when said tumbler is propelled by the key, may be 50 caused to pass into the notches or perforations in said key.

2. In locks, a single pivoted tumbler provided, first, with two or more projections adapted to pass into notches in its operating-key; 55 second, with an arm or projection, with which said key engages; and, third, with a catch or locking-projection for engaging with a hasp or shackle.

HARVEY C. ALDRICH.
